UNITED STATES PATENT OFFICE.

CECIL H. BOYULS, OF LOUISVILLE, KENTUCKY.

COLLAR-IRONING MACHINE.

Application filed February 13, 1922. Serial No. 536,386.

To all whom it may concern:

Be it known that CECIL H. BOYULS, citizen of the United States, residing at Louisville, in the county of Jefferson and State of Kentucky, has invented certain new and useful Improvements in Collar-Ironing Machines, of which the following is a specification.

This invention relates to laundry machinery and has special reference to a collar ironing machine for ironing the folds of turn down collars.

One important object of the invention is to improve the general construction of machines of this character.

15 A second important object of the invention is to provide an improved machine of this description having a series of collar holders which may be moved successively into ironing position.

20 A third important object of the invention is to provide an improved collar ironing machine having a series of collar holders arranged for successive positioning in operative relation to an oscillating iron.

25 A fourth important object of the invention is to provide a collar ironing machine having a continuously oscillating iron and an intermittently moving collar holder support provided with a circular series of collar holders arranged for successive movement into cooperative relation with the iron.

With the above and other objects in view, the invention consists in general of certain novel details of construction and combinations of parts hereinafter fully described, 35 illustrated in the accompanying drawings, and specifically claimed.

In the accompanying drawings, like characters of reference indicate like parts in the 40 several views, and:

Figure 1 is a side elevation of the complete machine.

Figure 2 is an enlarged side elevation of the upper part of the machine and showing the various parts in dotted lines, the view being to an enlarged scale.

Figure 3 is a front view of the upper part of the device, the view being partly in section.

50 Figure 4 is an enlarged detail section on the line 4—4 of Figure 3.

Figure 5 is a detail showing a stop plate used herewith.

55 Figure 6 is an enlarged detail of one edge of the iron.

Figure 7 is a section on the line 7—7 of Figure 3.

Figure 8 is a section on the line 8—8 of Figure 3.

Figure 9 is a detail view showing a portion on one of the journal bearing standards and certain parts associated therewith, the view disclosing the minor face of such standard.

This invention is designed to be supported 60 on an ordinary table 10, the top of the table being suitably cut away as at 11 to permit application of the device.

The main portion of the device is provided with a foundation or base ring 12 of 70 angle iron cross section, this ring being securely held on the table 10 by suitable bolts 13. Disposed centrally of this ring is a hub 14 which is connected to the ring by means of arms 15 so arranged that the hub is below 75 the plane of the base ring. In this hub there is formed a bore 16 having a reduced and threaded lower end 17. Screwed into this lower end of the hub is the threaded portion 18 of a guide sleeve 19 having a collar 20 of 80 slightly less diameter than the bore of the hub and is located at the upper end of the threaded portion 18. From this construction it is obvious that the guide sleeve is screwed into position from above. The 85 lower end of the portion 18 is provided with a wrench receiving end 21 and on the portion 18 is fitted a jam or lock nut 22. By this means the position of the collar within the hub may be adjusted vertically. 90

The ironing member includes a disk 23 having a depending boss 24 which is slidably and rotatably mounted in the upper end of the bore 16. The lower end of this boss is recessed at 25 to receive the upper end of the sleeve 19. Beneath the lower end of the boss 24 is located a ball bearing 26 and between this ball bearing and the collar 20 is a coiled compression spring 27 by means of which the ironing member is urged upward. In the upper end of the boss is a recess 28 wherein is located a ball bearing 29 on which rests the head 30 of a rod 31. This rod 31 passes downward through the boss and guide sleeve and to its lower end is attached a link 32 connected in turn to a treadle 33 pivoted to the floor at one end as at 34 and having its other end provided with a pedal 35.

By means of this pedal the iron may be 110

depressed at will and by means of the collar adjustment the force with which it is raised may be regulated. Around the periphery of the disk 23 is an upstanding wall or flange 36 having an ironing groove 37 extending around it, the groove being formed on its inner corner portion. A peripheral groove is also formed in this flange to receive an electric heating element 38 by which this portion of the iron is kept at the proper ironing temperature.

Depending from the foundation ring 12 is a bearing 39 and formed on the hub 14 in alinement therewith is a bearing 40. In these bearings is supported a shaft 41 on the other end of which is a pulley 42 driven by a belt 43 from any suitable motor. On this shaft is fixed an eccentric or cam 44 which is positioned between a pair of depending legs 45 preferably formed integrally with the disk 23, the cam bearing on wear plates 46 secured to the confronting faces of these legs. By this means rotation of the shaft 41 imparts a constant oscillatory movement to the disk and that this oscillatory movement is not affected by the vertical movement of said disk or iron.

Mounted on the ring 12 is a pair of diametrically disposed standards 47 having bearings 48 at their upper ends which receive the stub 49 of a collar support carrying frame 50. This frame is preferably of general quadrangular shape in cross section and on each side of the frame is formed a shallow cup shaped seat 51 and in each of these seats is mounted a collar support or holder 52 in the form of a short tube, this holder being preferably made of highly polished aluminum. On the inner or confronting faces of the standards 47 are guide strips 53 and between the guide strips of each standard slides a locking bar 54 which is held in position between said strips by cover straps 55. On each locking bar is a locking lug 56 arranged to enter one or the other of the peripheral notches 57 of a disk 58 fixed on the frame 50 about a respective stub shaft. On the lower end of each locking bar is a roller 59 working in a peripheral groove 60 forward on the disk 23. It is to be noted that the collar holders 52 are of suitable diameter to cooperate with the groove 37 so that the folded portion of a turn down collar can be properly ironed.

In operation the attendant places a collar on the uppermost form or holder 52 and pushes the collar down so that the collar is firmly fixed thereon. The edge is then dampered and the operator pushes the treadle down which releases the locking lugs and at the same time moves the oscillating iron down to clear the lowermost collar form thus permitting the frame 50 to be given a quarter turn and bringing the loaded form to a horizontal position and an empty form

uppermost. This second form is then loaded and during this time the moisture is soaking into the fold of the collar on the first form. A second depression of the treadle is made and the frame 50 given a second quarter turn. The release of the treadle allows the oscillating iron to come into contact with the collar on the first form and while the third form is being loaded the ironing operation is completed. It should be noted at this time that the peculiar shape of the form and the groove of the iron is such that the tap usually found on collars is at no time engaged by the iron and thus is not torn off as frequently happens with machines for this purpose as generally constructed. Moreover, an even pressure is exerted on the entire collar fold so that the ironing is accomplished without injury to the collar in any way. Upon depressing the treadle a third time the frame 50 is turned through its third quarter revolution and the first form assumes the unloading position and the fourth form takes the loading position. The finished collar is now removed from the first form and the latter will cool while the fourth form is being loaded.

Thus each form travels through a cycle of four positions, these being loading, soaking, ironing and unloading positions.

There has thus been provided a simple and efficient device of the kind described and for the purposes specified.

It is obvious that minor changes may be made in the form and construction of the invention without departing from the material principles thereof. It is not therefore desired to confine the invention to the exact form herein shown and described, but it is wished to include all such as properly come within the scope claimed.

Having thus described the invention, what is claimed as new, is:—

1. In a machine of the class described, an iron, and a series of collar holders mounted adjacent the iron for rotation about an axis at right angles to the axis of the iron and arranged to be successively moved into cooperative relation with said iron.

2. In a machine of the class described, an iron, a frame mounted to rotate in juxtaposition to the iron for rotation about an axis at right angles to the axis of the iron, and a series of collar holders mounted on said frame and arranged for movement successively into cooperative relation with the iron.

3. In a machine of the class described, an iron, means to oscillate the iron, and a series of collar holders mounted adjacent the iron for rotation about an axis at right angles to the axis of the iron and arranged to be successively moved into cooperative relation.

4. In a machine of the class described, an

- iron mounted for oscillation and for bodily linear movement on a fixed line at right angles to the plane of oscillation, a series of collar holders mounted on an axis arranged at right angles to the axis of oscillation of the iron for movement successively into alinement with the line of linear movement of the iron, means to continuously oscillate the iron, and means controllable by an operator for moving the iron to and from the alined collar holder. 5
5. In a collar ironing machine, an iron mounted for arcuate movement about a fixed axis and for linear movement along said axis, a collar holder mounted to swing on an axis at right angles to the first mentioned axis into and out of axial alinement with the iron, means to move the iron arcuately, and other means to move the iron along its axis. 10
6. In a collar ironing machine, an iron mounted for arcuate movement about a fixed axis and for linear movement along said axis, a collar holder mounted to swing into and out of axial alinement with the iron, means to move the iron arcuately, other means to move the iron along its axis, and a restraining mechanism arranged to prevent axial movement of the iron towards the collar holder except with the latter in alined position. 15
7. In a collar ironing machine, an iron mounted for arcuate movement about a fixed axis and for linear movement along said axis, a collar holder mounted to swing into and out of axial alinement with the iron, means to move the iron arcuately, other means to move the iron along its axis, and a restraining mechanism arranged to prevent axial movement of the iron towards the collar holder except with the latter in alined position, said restraining means being further arranged to hold the collar holder releasably from movement out of alinement. 20
8. In a collar ironing machine, an iron mounted for arcuate movement about a fixed axis and for linear movement along said axis, a collar holder mounted to swing into and out of axial alinement with the iron, means to move the iron arcuately, other means to move the iron along its axis, a bar mounted for guided linear movement and having connection with the iron to move linearly therewith, and a disk mounted to move with the holder and having a notch arranged to receive a portion of said bar at the time when the collar holder and iron are axially alined. 25
- 60 9. In a collar ironing machine, an iron mounted for oscillation about a fixed axis and for movement longitudinally of the axis, a frame mounted to rotate on an axis at right angles to the axis of the iron, a series of collar holders arranged peripherally around the frame and positioned to be brought successively into alinement axially with the iron, means to impart oscillatory movement to said iron, and other means to impart movement to the iron longitudinally of its axis at the will of the operator. 70
10. In a collar ironing machine, an iron mounted for oscillation about a fixed axis and for movement longitudinally of the axis, a frame mounted to rotate on an axis at right angles to the axis of the iron, a series of collar holders arranged peripherally around the frame and positioned to be brought successively into alinement axially with the iron, means to impart oscillatory movement to said iron, other means to impart movement to the iron longitudinally of its axis at the will of the operator, and a restraining mechanism arranged to prevent axial movement of the iron towards the collar holder except with the latter in alined position. 75
11. In a collar ironing machine, an iron mounted for oscillation about a fixed axis and for movement longitudinally of the axis, a frame mounted to rotate on an axis at right angles to the axis of the iron, a series of collar holders arranged peripherally around the frame and positioned to be brought successively into alinement axially with the iron, means to impart oscillatory movement to said iron, other means to impart movement to the iron longitudinally of its axis at the will of the operator, and a restraining mechanism arranged to prevent axial movement of the iron towards the collar holder except with the latter in alined position. 80
12. In a collar ironing machine, an iron mounted for oscillation about a fixed axis and for movement longitudinally of the axis, a frame mounted to rotate on an axis at right angles to the axis of the iron, a series of collar holders arranged peripherally around the frame and positioned to be brought successively into alinement axially with the iron, means to impart oscillatory movement to said iron, other means to impart movement to the iron longitudinally of its axis at the will of the operator, and a restraining mechanism arranged to prevent axial movement of the iron towards the collar holder except with the latter in alined position, said restraining means being further arranged to hold the collar holder releasably from movement out of alinement. 85
13. In a collar ironing machine, an iron comprising a circular disk having a peripheral upstanding wall provided with an ironing groove and having a central depending hub, a bearing for said hub wherein the lat- 90

ter may oscillate and move axially, a frame mounted to rotate on an axis intersecting the axis of the hub at right angles, a series of collar holders arranged peripherally around the frame and positioned to be brought successively into alinement axially with the iron, each of said holders consisting of a tubular cylinder having a diameter corresponding to the diameter of the ironing groove, means to impart oscillatory movement to the iron, and other means controlled by the operator for moving the iron longitudinally of its axis.

14. In a collar ironing machine, an iron comprising a circular disk having a peripheral upstanding wall provided with an ironing groove and having a central depending hub, a bearing for said hub wherein the latter may oscillate and move axially, a frame mounted to rotate on an axis intersecting the axis of the hub at right angles, a series of collar holders arranged peripherally around the frame and positioned to be brought successively into alinement axially with the iron, each of said holders consisting of a tubular cylinder having a diameter corresponding to the diameter of the ironing groove, means to impart oscillatory movement to the iron, other means controlled by the operator for moving the iron longitudinally of its axis, and a restraining mechanism arranged to prevent axial movement of the iron towards the collar holder except with the latter in alined position.

15. In a collar ironing machine, an iron comprising a circular disk having a peripheral upstanding wall provided with an ironing groove and having a central depending hub, a bearing for said hub wherein the latter may oscillate and move axially, a frame mounted to rotate on an axis intersecting the axis of the hub at right angles, a series of collar holders arranged peripherally around the frame and positioned to be brought successively into alinement axially with the iron, each of said holders consisting of a tubular cylinder having a diameter corresponding to the diameter of the ironing groove, means to impart oscillatory movement to the iron, other means controlled by the operator for moving the iron longitudinally of its axis, and a restraining mechanism arranged to prevent axial movement of the iron towards the collar holder except with the latter in alined position, said restraining means being further arranged to hold the collar holder releasably from movement out of alinement.

16. In a collar ironing machine, an iron comprising a circular disk having a peripheral upstanding wall provided with an ironing groove and having a central depending hub, a bearing for said hub wherein the latter may oscillate and move axially, a frame mounted to rotate on an axis intersecting

the axis of the hub at right angles, a series of collar holders arranged peripherally around the frame and positioned to be brought successively into alinement axially with the iron, each of said holders consisting of a tubular cylinder having a diameter corresponding to the diameters of the ironing groove, means to impart oscillatory movement to the iron, other means controlled by the operator for moving the iron longitudinally of its axis, a bar mounted for guided linear movement and having connection with the iron to move linearly therewith, and a disk mounted to move with the holder and having a notch arranged to receive a portion of said bar at the time when the collar holder and iron are axially alined.

17. In a collar ironing machine, an iron comprising a circular disk having a peripheral upstanding wall provided with an ironing groove and having a central depending hub, a bearing for said hub wherein the latter may oscillate and move axially, a frame mounted to rotate on an axis intersecting the axis of the hub at right angles, a series of collar holders arranged peripherally around the frame and positioned to be brought successively into alinement axially with the iron, each of said holders consisting of a tubular cylinder having a diameter corresponding to the diameter of the ironing groove, means to impart oscillatory movement to the iron, other means controlled by the operator for moving the iron longitudinally of its axis, a standard having said frame journaled therein, reciprocable bars mounted on said standards, rollers on the lower ends of said bars, said iron having peripheral grooves wherein said rollers engage, disks mounted axially on the frame and having peripheral notches corresponding in number and position to the collar holders, and lugs on said bars entering respective notches when the corresponding collar holder is alined with the iron.

18. In a collar ironing machine, an iron comprising a circular disk having a peripheral upstanding wall provided with an ironing groove and having a central depending hub, a bearing for said hub wherein the latter may oscillate and move axially, a frame mounted to rotate on an axis intersecting the axis of the hub at right angles, a series of collar holders arranged peripherally around the frame and positioned to be brought successively into alinement axially with the iron, each of said holders consisting of a tubular cylinder having a diameter corresponding to the diameter of the ironing groove, means to impart oscillatory movement to the iron, other means controlled by the operator for moving the iron longitudinally of its axis, and an electric heating element extending peripherally about iron adjacent the ironing groove.

19. In a collar ironing machine, an iron comprising a circular disk having a peripheral upstanding wall provided with an ironing groove and having a central depending hub, a bearing for said hub wherein the latter may oscillate and move axially, a frame mounted to rotate on an axis intersecting the axis of the hub at right angles, a series of collar holders arranged peripherally around the frame and positioned to be brought successively into alignment axially with the iron, each of said holders consisting of a tubular cylinder having a diameter corresponding to the diameter of the ironing groove, means to impart oscillatory movement to the iron, other means controlled by the operator for moving the iron longitudinally of its axis, a standard having said frame journaled therein, reciprocable bars having rollers thereon, said iron having peripheral grooves wherein said rollers engage, disks mounted axially on the frame and having peripheral notches corresponding in number and position to the collar holders, lugs on said bars entering respective notches when the corresponding collar holder is aligned with the iron, and an electric heating element extending peripherally about the iron adjacent the ironing groove.
20. In a collar ironing machine, a supporting ring, spider arms extending rearwardly and downwardly from said ring, a hollow hub carried by the spider arms centrally of the ring, a hub mounted in the hollow hub for oscillatory and sliding movement, a sleeve screwed into the bottom of the hub and provided with a collar, a spring resting on said collar and holding said second hub raised, a pull rod running through said sleeve and second hub and having a head on its upper end, a treadle secured to said pull rod whereby depression of the pedal depresses the second hub, a disk on the upper end of the second hub having a peripheral wall provided with an ironing groove, a pair of spaced arms depending from the disk, a rotary cam mounted between said arms, means to rotate the cam, a pair of standards extending up from said ring, a frame having stub shafts journaled in the upper ends of said standards, a series of cylindrical tubes projecting radially around the frame and constituting collar holders, said tubes being arranged for successive positioning over said ironing grooves, a pair of disks mounted concentrically of the axis of the frame and each having peripheral notches corresponding in number and position to the collar holders, sliding bars in operative connection at their lower ends to said iron disk, and lugs on said bars engageable in the notches of the pair of disks.

In testimony whereof I affix my signature.

CECIL H. BOYULS.
